UNITED STATES PATENT OFFICE.

WILLIAM C. AYERS, OF ARLINGTON, TEXAS, ASSIGNEE OF ONE-FOURTH TO ERNEST B. CANTRELL AND EIGHT ONE-HUNDREDTHS TO TOM L. RAYDOLINE, BOTH OF DALLAS, TEXAS.

INVENTION IDENTIFICATION CERTIFICATE FOR MOTOR VEHICLES.

Application filed June 8, 1923. Serial No. 442,612.

To whom it may concern:

Be it known that I, WILLIAM C. AYERS, a citizen of the United States, residing at Arlington, in the county of Tarrant and State of Texas, have invented certain new and useful Improvements in Identification Certificates for Motor Vehicles, of which the following is a specification.

This invention relates to an identification certificate for use in connection with the identification of motor vehicles, and to this end the invention aims to provide in a manner as hereinafter set forth, means whereby an owner of a motor vehicle can readily identify the same when occasion requires, more particularly when the vehicle has been stolen and the engine and license numbers removed, or when the vehicle has been disguised in any manner.

20 A further object of the invention is to provide, in a manner as hereinafter set forth, a motor vehicle identification certificate, not only containing all of the regular designations, indications or data with reference to the identification record of the vehicle, but in addition thereto a fac-simile record on a pictorial representation of a motor vehicle of an identification code as applied to a concealed or secret part or parts 25 of the vehicle so that upon a comparison of the record on the certificate with that of the code as applied to the vehicle, the latter can be readily identified by its owner.

Further objects of the invention are to 30 provide an identification certificate for the purpose set forth, which is simple in its arrangement, accurate, thoroughly efficient for its purpose of identifying, capable of having the identifying data conveniently applied thereon, and inexpensive to manufacture.

With the foregoing and other objects in view, the invention consists of the novel form of identification certificate as herein-after more specifically described and illustrated in the accompanying drawing, wherein is shown an embodiment of the invention, but it is to be understood that changes, variations and modifications can be had 45 which fall within the scope of the claims hereunto appended.

The drawing illustrates a front elevation of an identification certificate for motor vehicles, in accordance with this invention.

Referring to the drawing in detail, an identification certificate in accordance with this invention comprises a body portion 1, formed of any suitable material, such as paper or parchment, and which is provided with a conventionally designated space 2 for the reception of the number of the certificate and is furthermore provided with a conventionally designated space 3 for the reception of the date of issuance of the certificate. The space 2, as well as the space 3 is surrounded by lines 4, of any suitable color. The spaces 2 and 3 preferably are arranged near the upper end of the body portion 1, the latter being rectangular in contour. Arranged approximately centrally of the body portion 1, are the pictorial representations of a pair of motor vehicles, as indicated at 5, 6, and which are disposed at an inclination, extend in opposite directions with respect to each other, as well as extending towards each other, and each of which has one side of the hood removed so as to show the engine thereon. The pictorial representation 5 shows one side of an engine 7, while the pictorial representation 6 shows the opposite side of the engine 7.

The body portion 1, between the pictorial representations 5 and 6, is provided with a conventionally designated line 8 for the reception of the name of the make of the vehicle, a conventionally designated line 9 for the reception of the number of the engine of the car, a conventionally designated line 10 for the reception of the name of the model of the car, and a conventionally designated line 11 for the reception of the year in which the car was built.

The body portion 1 is furthermore provided at one side of the pictorial representation 5, that is near the lower end of said representation, with a conventionally designated line 12 for the reception of a highway number and below said line 12 with a conventionally designated line 13 for the reception of the style or kind of car, and the body portion 1, at one side of the lower part of the pictorial representation 6, is provided

with a conventionally designated line 14 for the reception of the license number of the car, and below the line 14 with a conventionally designated line 15 for the reception 5 of the letters of the identifying code.

Arranged below the pictorial representation 5, 6, and extending transversely of the body portion 1, is an identifying code consisting of the letters of the alphabet, as indicated at 16, the digits 1 to 9 as indicated at 17, and a cipher as indicated at 18. The letters of the alphabet are arranged in two transverse rows and each letter within a rectangular space 19 formed by transverse and longitudinal lines 20, 21 respectively. Certain of the longitudinal lines are extended, as at 22, and in connection with a transverse line 23 and one of the transverse lines 20 rectangular spaces 24 are provided 20 for the digits 17. A pair of intermediate longitudinal lines 21 are extended as at 25, and in connection with the transverse line 26 and the transverse line 23 a rectangular space 27 is provided for the cipher 18.

25 Below the code, the body portion 1, is provided with conventionally designated lines 28, 29, 30, 31, 32 and 33 for the reception respectively of the owner's name, his street 30 number, the city in which he resides, the county in which the city is situated and State to which the county belongs, and further for the name of the county representative.

The pictorial representation 5 or 6 of the 35 motor vehicle is adapted to have positioned thereon letters or digits of the code which have been selected and stamped on concealed parts or secret points of a motor vehicle, so that the letters or digits will appear on a 40 pictorial representation at points corresponding to the points on which they have been applied to the motor vehicle. By way of example, it would be assumed that the letters A, C and W have been applied to the 45 motor vehicle for identification purposes and that the said letters A, C and W are then placed on a pictorial representation at points corresponding to the points at which they appear on the vehicle. From the selected letters of the code, such letters corresponding to those which have been placed 50 on the vehicle, extend arrows for indicating on the pictorial representation the position of such selected letters and with the position 55 of the letters on the pictorial representation corresponding to the points at which the letters have been placed on the vehicle. The arrows are indicated at 34, and these 60 arrows not only indicate the position of the letters as applied to the vehicle, but also designate the letters which have been selected from the code.

It is to be understood that any combination 65 of letters or combination of letters and digits can be arranged at any secret or con-

cealed point or points on the vehicle and that after being cut, stamped or otherwise applied to the vehicle the pictorial representation of the vehicle will have applied thereto, such combination at places corresponding to the position of the combination on the vehicle.

When using the certificate, the certificate will preferably be issued in quadruplicate and one copy will be attached to the insurance policy, a copy sent to the insurance company, another copy forwarded to the automobile theft bureau, and the remaining copy retained in the office of the agent writing the policy, or in other words, the certificate so describing one's ownership of the vehicle will be made out for each vehicle owner, having the car insured and a copy will be placed with the insurance policy and other proper authorities.

85 The code provides means for identifying a stolen vehicle when the engine and license numbers have been removed or when the car has been disguised and as the code is applied to secret or concealed parts of the vehicle, the tampering therewith is reduced to a minimum.

90 The code letters selected, if desired, may be the initials of the name of the owner of the vehicle, and although the code is illustrated as consisting of letters of the alphabet and digits, so that either or a combination of both can be used, yet it is to be understood that any suitable code capable of carrying the invention into effect can be employed.

100 The identification certificate, not only includes means to provide for the identifying of a vehicle, through the medium of an identifying code, but furthermore contains all the regular designations, indications or 105 data usually found upon a motor vehicle.

110 Although the preferred embodiment of the motor vehicle identification certificate, in accordance with this invention, is as described and illustrated, yet it is to be understood that changes in its form can be had, such as adding thereto the name of the association issuing the certificate or that the certificate can be ornamented in any suitable manner or that, changes in the arrangement of the data receiving means, can be had which will fall within the light of the 115 invention as claimed.

115 What I claim is:—

120 1. An identification certificate for motor vehicles comprising a body portion, means thereon to provide a code of selective identifying indicia, means on said body portion to constitute the pictorial representation of a motor vehicle with the engine exposed for recording thereon indicia selected from said code at points corresponding to the points of a motor vehicle upon which have been applied like identifying indicia selected from said code, and said body por-

tion further provided with conventionally designated means for the recording of the regular designations carried by a motor vehicle and further for the reception of the 5 vehicle owner's name and his address.

2. An identification certificate for motor vehicles comprising a body portion, means thereon to constitute a code of selective identifying indicia, means on said body 10 portion to constitute the pictorial representation of a pair of oppositely disposed motor vehicles having the engine exposed and providing means for recording thereon indi-

cia selected from said code at points corresponding to the points of a motor vehicle 15 upon which have been applied like identifying indicia selected from said code, and said body portion further provided with conventionally designated means for the reception of the regular designations carried by a motor vehicle and further for the reception of the vehicle owner's name and his address. 20

In testimony whereof, I affix my signature hereto.

WILLIAM C. AYERS.
